ANNEALING FURNACE

James C. Woodson, Cleveland, Ohio, assignor to
 Lee Wilson Sales Corporation, Cleveland, Ohio,
 a corporation of Ohio

Application September 28, 1937, Serial No. 166,052
 Renewed June 14, 1938

2 Claims. (Cl. 266—5)

This invention relates to the art of annealing and in particular to a furnace of the cover type and a method practiced with the aid thereof.

In the annealing of sheet or strip material in cover type furnaces, it has been the practice heretofore to place a charge of material on a furnace base, enclose it within a protective cover, and lower a heating cover thereover. The material being annealed has been heated by the radiation of heat from the exterior of the charge toward the interior. It has also been proposed heretofore to expedite the heating of material in coil form by radiating heat from the space within the coil to the inner layers thereof.

15 The sizes of steel sheets and the width of steel strip required by the users thereof have increased materially in recent years, necessitating large furnaces for the annealing thereof. When these furnaces are used for the annealing of sheets or coils of the smaller sizes, however, as is sometimes necessary, the efficiency of the annealing operation is impaired because of the considerable time required for the heat delivered by the furnace cover to soak through the 20 stacks of material disposed on the furnace base from the outside of such stacks through the mass thereof to the inner layers or surface.

I have invented a novel form of furnace of the cover type, which is particularly adapted for simultaneously annealing a plurality of stacks or charges of material disposed on a suitable supporting base in spaced relation, and preferably in aligned rows. In accordance with my invention, I provide the furnace cover with heat-radiating means in the form of radiant tubes along the side walls thereof and mount burners in said tubes, whereby combustion gases passing therethrough heat them to radiant temperature so that they radiate heat to the exteriors of a 25 plurality of stacks or charges in aligned rows from the outer sides thereof. I also provide heat-radiating means similar to those above mentioned between adjacent rows of stacks or charges and suspend them from the furnace 30 cover for radiating heat to stacks in each of two adjacent rows from the space intermediate thereof. I thus expedite the heating of the charges to the desired annealing temperature by supplying heat to each charge from opposite 35 sides thereof.

The general arrangement of heating tubes outlined above is also disclosed and claimed in my copending application Ser. No. 237,423, which is in part a continuation hereof.

The invention may be more fully understood,

both as to the structural details and the procedural steps involved, by referring to the following description and the accompanying drawings illustrating a present preferred embodiment and practice. In the drawings:

Figure 1 is a sectional view through a furnace according to the invention along a central longitudinal vertical plane; and

Figure 2 is a sectional view along the line II—II of Figure 1 and indicates at the line I—I 10 the plane on which the section of Figure 1 is taken.

As clearly shown in the drawings, the furnace comprises a base 10 and a cover 11, removably disposed thereon. The base 10 comprises a 15 structural frame 12, a floor sheet 13, a refractory hearth 14, laid thereon, including a peripheral curb 15, and a bottom plate 16, on which the charge supports 17 are disposed in spaced relation, preferably aligned in parallel rows as 20 illustrated. The bottom plate 16 is covered with granular sealing material 18. Protective covers 19 are disposed over charges 20 resting on the supports 17, and the lower edges of the covers project into the sealing material 18. The charge 25 20 may be one or more coils of strip or a stack of sheets.

The cover 11 comprises refractory side walls 22 and a roof 23 assembled within a frame composed of structural members 24 and sheathing 30 plates 25. The furnace cover is open at the bottom and is adapted to rest on the edge of the base 10. The latter is provided with a sealing channel 26 containing granular or other sealing material with which a flange 27, depending from the lower edge of the cover 11, is adapted to cooperate. Heat radiators in the form of heat exchange tubes 28 are spaced along opposite side walls (preferably the longer side walls) of the furnace cover.

Each of the tubes 28 has a burner 29 mounted in the lower end thereof. The burners 29 are connected to fuel supply mains 30. An igniter electrode 31 is disposed adjacent the tip of each burner and is connected to an energizing transformer 32. Fuel supplied to the burners 29 from the mains 30 is thus ignited and combustion within the tubes 28, supported by atmospheric air induced into the lower ends of the tubes, heats the latter to radiant temperatures whereby heat is radiated to the exteriors of the aligned stacks or charges from the outer sides thereof. After passing through the tubes 28, the combustion gases are discharged into exhaust manifolds 33, carried on the cover 11.

The remaining side walls 22 are provided with heat exchange tubes 34 extending inwardly therethrough to about the middle of the length of the furnace cover. The tubes 34 are arranged in vertical bands and include, in addition to the horizontal sections 35 thereof, vertical sections 36 extending upwardly through the roof. The tubes 34 are suspended on hangers 37 including rods 38 depending from the furnace roof and stirrups 39 carried thereby. The lower ends of the stirrups 39 engage guide and bearing plates 40, secured to the bottom plate 16 of the base 10. The outer ends of the horizontal sections 35 of the tubes 34 are provided with burners 41, similar to those shown at 29, and fuel supply mains 42 are connected thereto. The tubes 34 are heated like the tubes 28 by the combustion of fuel therein and radiate heat to the exteriors of the rows of stacks or charges on each side thereof from the space therebetween. After traversing the tubes 34, the combustion gases are discharged into a collector box 43 on the furnace roof. Exhaust ducts 44 extend laterally from the box 43 to downcomers 45. The latter cooperate with fixed exhaust passages 46 leading to a stack (not shown) or other means for finally disposing of the gases. Connections 47 between the manifolds 33 and the downcomers 45 provide for the disposition of combustion gases discharged from the tubes 28.

30 The openings in the roof of the furnace cover through which the vertical portions 36 of the heat exchange tubes 34 extend are closed by sealing channels 48 extending above the openings and depending flanges 49 extending downwardly thereinto from the upper ends of the vertical tube sections. The channels are provided with granular or other sealing material. This type of seal permits expansion and contraction of the vertical tube sections without injury to the furnace roof.

40 It will be apparent from the foregoing description that the invention provides an annealing furnace and method characterized by numerous advantages over the previous practice in this art. 45 It will be understood that the furnace of my invention is utilized by placing the charges on the supports 17 after raising cover 11 from the base 10. The protective covers 19 are then placed and the heating cover 11 lowered onto the base. 50 After the burners have been ignited and the charges brought up to the proper temperature, the furnace cover is removed to another base having thereon charges for annealing, the charges

on the base 10 remaining thereon until cooled substantially to atmospheric temperature, after which the protective covers 19 are removed and the charges unloaded.

Because of the disposition of heating elements between adjacent parallel rows of aligned charges, I am able to heat the latter to the desired temperature in a much shorter time than would be required under the previous practice of radiating heat to the charges from the outer sides thereof only. The novel construction for this purpose shown herein is simple in character and relatively inexpensive so that the increased production rendered possible thereby is not accompanied by any penalty in the form of a material increase in the cost of construction or operation of the equipment. 10 15

Although I have illustrated and described herein but a preferred embodiment and practice of the invention, it will be understood that changes 20 in the construction and procedure disclosed may be made without departing from the spirit of the invention or the scope of the appended claims.

I claim:

1. In a furnace, a base and a cover cooperating therewith, hangers depending within said cover, heat-radiating means suspended on said hangers, and guide and bearing plates on said base adapted to receive and support the lower ends of said hangers. 25

2. In an annealing furnace, a base, a plurality of supports for charges of material arranged on said base in spaced rows, a cover having side walls, end walls, and a roof, adapted to be disposed on the base and overlie all said supports and charges thereon, heat-exchange tubes extending upwardly along said side walls from points near the lower edges thereof effective to deliver heat to the outer sides of charges on said supports, substantially horizontal heat-exchange tubes extending inwardly from said end walls, and suspended from said roof between adjacent rows of charge supports for radiating heat to the inner sides of said charges, exhaust tubes connected to said last-mentioned tubes and extending substantially vertically through said roof, an exhaust duct communicating with said tubes and extending downwardly along one of said side walls, and a manifold extending along said one of said side walls, said manifold communicating with said first-mentioned tubes and with said duct. 30

JAMES C. WOODSON.
